Barking, England

Application October 18, 1939, Serial No. 300,038
In Great Britain October 25, 1938

2 Claims. (Cl. 220—42)

This invention relates to containers made of sheet metal or moulded material and more particularly to containers in which it is desirable that the lid should provide an air-tight or substantially air-tight seal; this is the case with, for example, containers for face-cleansing pads, ointments, scented powders and like goods liable to deterioration when exposed to the air.

It is known to employ for this purpose a lid which has a vertically-tapered flange engaging the edge of the opening in the container proper.

In the practical use of such containers we have found that there is on some occasions the possibility of the lid "springing up" at one portion of its circumference, due presumably to the pressure of the air trapped in the container when the lid is placed in position. This may happen, for example, if there is a local variation in the thickness of the metal as a result of which the lid is depressed more strongly at one point than another. Whilst this difficulty does not arise if the lid is positioned uniformly and firmly it is naturally desirable to prevent it from arising at all so that the user does not need to take special care in obtaining a tight fit. For the purpose of obviating the said difficulty we shape the lower edge of the rolled-over portion at the top of the container body so that, during the insertion of the lid, air may escape from the body whilst nevertheless the lid provides an air-tight or substantially air-tight fit when fully inserted.

In order that the invention may be more readily understood reference will now be made to the accompanying drawing in which one embodiment is shown by way of example.

The single figure of the drawing is a sectional view showing one embodiment of the invention.

The container shown consists of a cup-shaped body having a substantially cylindrical side wall 10 and a flat bottom 11 integral therewith and of a lid 12. The lid 12 has an upwardly-dished centre portion 13, a V-shaped flange 14 and a bead-like rim 15 which extends outside the cylindrical wall 10 to provide a finger-grip by which the lid may be readily removed. The outer tapered side 16 of the flange 14 provides for the necessary tightness of fit with the top of the container and to facilitate this result the upper edge of the cylindrical wall 10 of the container is rolled over inwardly as shown at 17. With this construction there is no difficulty in removing the lid notwithstanding the tapering of the flange 14 and its tight engagement with the rolled edge 17 since the finger grip 15 permits ready removal of the lid.

For the sake of appearance and additional strength the lower portion of the cylindrical wall 10 may be formed with a bead 18. In the preferred form the lid and the container are each produced from a single piece of sheet metal by appropriate drawing and/or stamping operations. In order to improve the tightness of fit between the lid and the container the edge 17 of the cylindrical wall 10 is tapered and is made more resilient than the lid so that it gives to some extent when the lid is inserted. The initial taper angle of the said edge is preferably slightly greater than that of the flange. Although in some instances the difference in resilience may be attained by strengthening the lid, e. g., by dishing, in the manner shown at 13, the same result may be obtained by using different materials or different thicknesses. For example the body of the container may be made of aluminium and the lid of tinplate.

As shown it is preferable that the depth of the finger grip 15 be such that the bight formed between it and the side 16 of the flange 14 abuts against the top of the rolled edge 17 of the container to limit the extent to which the lid may be inserted.

It will be observed that the portion 17 is shaped to avoid "springing up" of the lid at one portion of its circumference due to trapping of the air in the container when the lid is placed in position, whether or not the user takes care to position the lid uniformly and firmly. For this purpose the lower edge of the portion 17 is provided with notches or perforations. In the form shown the notches are in the form of serrations of shallow saw-tooth form. There may conveniently be eight teeth 29 jointly extending over the periphery. During the initial portion of the operation of inserting the lid 12 air may escape through the passages formed by the teeth but when the lid is completely inserted, as shown in the right-hand half of the figure, it blocks the said passage and thus renders the container air-tight or substantially air-tight.

45 We claim:

1. A container comprising in combination a body having an opening defined by a rolled-down edge and a lid having a tapered flange engaging said edge and a finger-grip, said edge and flange providing resilient coacting sealing surfaces and said edge being notched at its periphery to form passages for escape of air from the body only during the insertion of the lid, and the angle of taper of said flange being such that upon application of the lid the initial contact between the op-

posing faces of said flange and rolled-down edge occurs along a line intersecting said passages.

2. A container comprising in combination a body having an opening defined by a rolled-down edge and a lid having a tapered flange engaging said edge and a finger-grip, said edge and flange providing resilient coating sealing surfaces and said edge being serrated at its periphery to form

5 passages for escape of air from the body only during insertion of the lid, and the angle of taper of said flange being such that upon application of the lid the initial contact between the opposing faces of said flange and rolled-down edge occurs along a line intersecting said passages.

SYDNEY CHARLES LOMAX.

HARRY KNIGHTSON.
